UNITED STATES PATENT OFFICE.

JOHN T. McENNANEY, OF ATLANTA, GEORGIA.

PAINT-MIXER.

SPECIFICATION forming part of Letters Patent No. 366,784, dated July 19, 1887.

Application filed September 23, 1886. Serial No. 214,385. (No model.)

To all whom it may concern:

Be it known that I, JOHN T. McENNANEY, a citizen of the United States, residing at Atlanta, in the county of Fulton and State of Georgia, have invented a new and useful Paint-Desiccator; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of this invention is to produce a machine for the purpose of drying mineral paint by artificial heat, and at the same time to pulverize it and leave it in a more desirable condition for the market.

The invention consists in a revolving cylinder in which is a perforated steam-pipe, and which is provided with projecting teeth which are set diagonally to the axis of the cylinder, and as the cylinder revolves in a casing the diagonal teeth are so set as to force the material toward and out of one end of the cylinder. This casing is surrounded by another, leaving an annular steam-space between the two casings, which are connected at the top in a way to leave an opening its entire length, and suitable means for feeding the machine, and other details, as will be hereinafter fully described.

In the accompanying drawings, Figure I is a side view, partly in section, showing most of the details. Fig. II is a cross-section on the line A. B. Fig. III is a longitudinal section of the dovetailed guiding-strip, the tooth-carrying strip, and the adjusting-strip.

In the several figures, like reference-marks referring to like parts, 1 is a cylinder having longitudinal grooves 2, into which are dovetailed slides 3. The strips 4 have teeth 5 diagonally set on one side, the other side consisting of inclined planes 6.

7 are strips provided with inclined planes on one side, similar to but in a direction the reverse to that of inclined planes 6. The slides 3 have rectangular holes adapted to receive the diagonally-set teeth on the strips 4. For the purpose of adjusting the teeth and taking up any wear, the strips 7 are adjusted endwise by set-screws 8 and the strips 4 are held down by the set-screws 9. The heads 10 of the cyl-

inder are provided with square inward projections to insure their being located centrally to the cylinder, and the cylinder is provided with lugs 11, to which are bolted the heads 10. The heads are also provided with stuffing-boxes 14 and glands 15. The cylindrical casing 17 is provided with a narrow opening at the top, the sides of which opening, extending 50 to its length, unite the inner and outer shell of the casing, and provide an opening through which the machine is fed by the worm 19, which is revolved in the cylinder 24 by the worm-gears 20 and 21 on the shaft 22, and forces 55 the material through the tubes 23, which are located in the top of the casing. 25 is a hopper to hold the material, and from which it is fed by the worm. The cylinder 1 is driven by the gear 30, which is preferably made integrally 60 with one of the cylinder-heads, and in turn is driven by the pinion 31 on the shaft 32.

The pinion-shaft is supported by the brackets 33, and will carry any suitable pulley to receive the belt to drive the machine. The 75 scraper 36 has teeth projecting downwardly through the opening in the top of the cylindrical casing, and, as the teeth 5 are set spirally on the cylinder 1, the scraper has a longitudinally-reciprocating motion for the purpose of 80 preventing the contact with the teeth 5. To produce this reciprocating motion of the scraper, the projecting arm 34 engages with the cam 35 on the cylinder 1. The steam-pipe 40 passes through the cylinder, and is perforated in that part which is within the cylinder. 85 The steam-pipe after passing through the cylinder has a return-bend and enters the cylindrical casing between the outer and inner shells.

The cock 41 is provided for the purpose of drawing off the water resulting from the condensation of steam in the space between the inner and outer shells of the casing. 42 is an opening for the discharge of the material.

In the preparation of mineral paint it is commonly freed from foreign matter by the use of water, which leaves it in a wet condition, in which condition it is put into the hopper 25, from which it is fed into the annular space between the cylinder and casing by being forced through the tubes 22 by the worm 19.

The cylinder running in the direction indicated by the arrow, Fig. II, will carry it around

the cylinder and the teeth setting obliquely toward the other end. The cylinder and double casing being heated by steam—the first by the steam that escapes through the perforations in the pipe and the second by the steam that is carried through the return-bend—will gradually heat the material, which, as it passes the opening in the top, will throw off its moisture, and, being constantly agitated, will be prevented from forming into lumps, thereby obviating the necessity for a subsequent grinding. The inner side of the casing is curved outwardly until the continuation forms the side of the opening at the top, under which the material enters as it is fed to the machine, for the purpose of providing an easy entrance that will not have any tendency to stop the material and crowd it out at the top.

The teeth on the cylinder 1 being set obliquely and spirally are so arranged with reference to their distance from each other that they will scrape the whole inner surface of the casing, and the reciprocating scraper prevents the adherence near the discharging end of the material to the cylinder.

It is found that a steam-desiccator arranged as above described will dry mineral paint without discoloration and leave the material in a pulverous condition.

I am aware that it is not new to heat desiccating cylinders by steam, or to supply them with apparatus to keep their contents in motion and gradually force said contents toward one end of the cylinder as it becomes drier, and finally eject it from the cylinder through a suitable opening formed for that purpose. I therefore limit my claims to the specific com-

bination of devices by which I accomplish these purposes.

Having described my invention, what I claim as new, and desire to secure by Letters Patent of the United States, is—

1. In a paint-desiccator, the combination of a cylindrical casing having an opening through the top for the escape of moisture, a steam-heated cylinder provided with oblique teeth arranged to scrape the inner surface of the casing, and a reciprocating scraper to scrape the cylinder, arranged substantially as described. 45

2. In a paint-desiccator, the combination of the cylinder 1, having teeth set obliquely and spirally on the cylinder, and a reciprocating scraper, with a casing having a double shell and an opening at the top for the escape of moisture, and a perforated steam-pipe passing through the cylinder and entering the annular opening between the shells of the casing, substantially as described. 55

3. In a paint-desiccator, as a means of adjusting the teeth in a cylinder, the combination of the strip 3, having holes for the teeth to pass and carry the screws 9, the strip 4, one side consisting of one or more inclined planes carrying the teeth 5 and the strip 7, one side 65 of which also consists of one or more inclined planes, and the screws 8, substantially as described. 60

In testimony whereof I affix my signature in presence of two witnesses.

JOHN T. McENNANEY.
